INTEGRATING MECHANISM

Bernard E. Saltzman, Dorchester, Mass.

Application April 13, 1943, Serial No. 482,889

6 Claims. (Cl. 235—61)

The object of this invention is to provide a novel and improved apparatus for the integration of the value of a variable element with respect to time. The invention is embodied in a mechanism including a shaft which is driven uniformly by a suitable timing mechanism such as a clock. Another shaft is rotated in proportion to the movements of the variable element which is to be integrated. Suitable clutch and gear mechanisms are operated by the said two shafts whereby to operate a counting device for indicating the result of the integrating operation. The apparatus may be used for the purpose of integrating rates in a wide variety of instruments in order to obtain or give total values. For example, the apparatus may be used for converting rates of speed, steam, air and water consumption, etc. into total quantities. In the drawings illustrating the invention

Fig. 1 is a view, partly in section and partly broken away of an integrating apparatus embodying the invention.

Figs. 2 and 3 are bottom views of a clutch gear, trip lever and associated parts shown in Fig. 1, showing these elements in two different positions.

Figs. 4 and 5 are top views of the clutch gear and associated parts in two different positions.

Fig. 6 is a diagram illustrating the clutch drive shown in Figs. 1 to 5.

Figs. 7 and 8 are diagrams illustrating the operation of the apparatus.

Referring first to Fig. 1 the integrator 6 is contained within a casing 110. A telemotor 111 is suitably connected to the variable element, not shown, so as to duplicate the movements thereof by rotation. The motor drives a worm 112 which rotates a worm gear 113 which rotates about but not with a gear shaft 114. The gear 113 carries a trip pin 115 hereinafter called the movable trip. The pin is positioned in operative positions by the rotations of the gear 113 according to the variable measurements of the movements of the variable. A fixed trip pin 116 is suitably secured to the casing 110. Shaft 117 is uniformly driven from a suitable clock mechanism, not shown, and this shaft operates the integrator. The shaft 117 drives a gear 118 in mesh with a clutch gear 119 which also rotates about but not with the shaft 117. The clutch gear carries on its lower side a pivoted trip lever 120 with two trip arms 121 and 122. The lever has a third depending arm 123, Figs. 2 and 3, which alternately engages two pins 124 and 125 carried on a synchronizing ring 126 to rotate the latter back and forth circumferentially. The ring 126 is slidably supported in

the spokes of the gear 119 as indicated at 127. Secured to the shaft 114 on the upper side of the clutch gear 119 is an inner clutch drum 128 adapted to be engaged by and driven by the inner driving surfaces of three clutch shoes 129, Fig. 4. An outer clutch drum 130 is suitably mounted to rotate about but not with the shaft 114. The outer drum is adapted to be engaged by and driven by the outer driving surfaces of the three clutch shoes 129, Fig. 5.

The clutch shoes are pivoted at 131 upon the upper side of the gear 119 and each shoe has a slot 132 in which moves a pin 133, the three pins 133 being carried by the synchronizing ring 126. Thus the two pins 124 and 125, Fig. 2, point in one direction away from the ring 126. The three pins 133 point in the opposite direction from the ring. The trip lever 120 moves from the one side of the shaft 114 to the other side to shift the synchronizing ring. The lever is shifted alternately by engaging the two trip pins 115 and 116 as will be explained. The final movement of the trip lever is a quick flip accomplished by a suitable spring 134 in a well known manner. Thus the clutch shoes are thrown quickly from one clutch drum into engagement with the other clutch drum. The pressure of the clutch shoes on either drum is provided by the action of springs 135 operatively attached to the shoes and to the clutch gear as shown. Referring back to Fig. 1 the outer clutch drum is carried by a gear 136 in mesh with a gear 137 which rotates a counter shaft 138 clockwise, the counter not being shown. A train of gears 139, 140 and 141 drives the shaft 138 counter-clockwise directly from the shaft 114 on which the inner drum is fast.

The train of driving elements in the clutch mechanism may now be conveniently traced as follows, Fig. 6. From the clock gear 118 to clutch gear 119, via clutch shoes 129 to the inner clutch drum 128, to gears 139, 140, 141 to counter shaft 138. When the clutch shoes are thrown on the outer drum the drive is from the gear 118 to clutch gear 119, via the clutch shoes 129 to outer drum 130, its gear 136 and gear 137 to the shaft 138. It will later be shown that the net difference between the forward and backward rotations of the counter shaft 138 is the distance in feet travelled up or down as measured by the altitude meter.

The following is a brief explanation of the operation of the integrator mechanism. The trip pins 115 and 116 are freely rotating rollers which trip or throw the trip lever from one side to the

other when the trip arms 121 or 122 engage the pins. The position of the movable trip 115 is determined by the turning of its supporting gear 113 which is operated from the telemotor 111, the maximum motion of gear 113 being 180 degrees either way from neutral. The trip arm 121 is acted upon by the trip 116 while the trip arm 122 is acted upon by the trip 115, the arms and pins being in different corresponding planes as shown in Fig. 1. In Fig. 7, where the trip 115 is shown in neutral position, the clutch gear is rotated counter-clockwise and the arm 121 has just struck the trip 116 to throw the trip lever to the right and the clutch shoes are now driving the inner clutch drum which drives the counter forward. The arm 122 now extends beyond the edge of the gear 119. After 180 degrees of rotation the arm 122 will strike the trip 115 and trip the lever 120 to the left. Now the shoes engage the outer drum which drives the counter backwards. The counter has therefore been driven 180 degrees forward and 180 degrees backward or a net motion of zero.

When it is desired to integrate a selected variable, the telemotor 111 is connected to the variable so as to duplicate by rotations the movements of the variable. The clock shaft 117 is connected to a time clock mechanism to be driven thereby for integrating the variable with respect to time. During the operation the gear 113 is therefore rotated in proportion to the value of the variable. By way of the operations of the clutch and the gearing means the final net movement resulting from these operations is shown and may be read upon the counter.

I claim:

1. In apparatus for integrating the value of a variable with respect to time, a uniformly rotating gear, a shaft about which said gear is freely rotatable, a counter, reversing clutch for transmitting the rotations of said gear to said counter comprising a first clutch drum fast on said shaft, a second clutch drum supported to rotate freely about said shaft, clutch shoes mounted on said uniformly rotating gear and adapted to alternately engage the said two clutch drums, a tripping lever pivoted on said uniformly rotating gear for operating the clutch shoes to alternately engage the one clutch drum to rotate said counter in one direction and to alternately engage the other clutch drum to rotate said counter in the opposite direction, a plurality of gears for transmitting the rotations of the said two clutch drums, respectively, to the said counter to operate the same in opposite directions as aforesaid, a fixed trip and a movable trip for timing the operations of said tripping lever and mechanism for operating said movable trip with respect to the said tripping lever to actuate the latter in proportion to the value of the variable being integrated.

2. In apparatus for integrating the value of a variable with respect to time, a gear, means for rotating said gear at a speed representative of time, a shaft about which said gear is freely rotatable, a counter for indicating the value of the variable being integrated, a reversing clutch for transmitting the rotations of said gear to said counter comprising an inner clutch drum fast on the said shaft, an outer clutch drum supported

70

to rotate freely about the said shaft, clutch shoes mounted on said time driven gear and adapted to alternately engage the said clutch drums, tripping means on said gear for operating the clutch shoes to alternately engage the said clutch drums to rotate the counter in alternate opposite directions, a plurality of gears for transmitting the rotations of the said inner and outer clutch drums, respectively, to the said counter to operate the same in opposite directions as aforesaid, a fixed trip adapted to be engaged by said tripping means to operate the same to move the said clutch shoes into engagement with the said inner clutch drum, a movable trip adapted to engage said tripping means to move the said clutch shoes into engagement with the said outer clutch drum and means actuated in proportion to the value being integrated for operating the said movable trip.

3. In apparatus according to claim 2, a spring on each of said clutch shoes for shifting the same instantaneously from the one clutch drum to the other clutch drum when the said clutch shoes are actuated by the said tripping means.

4. In apparatus for integrating the value of a variable with respect to time, a counter for indicating the value of the variable being integrated, a uniformly driven gear, a second gear, means for oscillating the second gear in proportion to the value of the variable being integrated, a rotatable reversing clutch for operating said counter in response to the movements of the said two gears, respectively, a tripping device mounted on said uniformly driven gear for operating the said clutch, a fixed trip element adapted to be engaged by the said tripping device to cause the latter to operate the said clutch rotatably in one direction, a second trip element mounted upon said oscillating gear and adapted to engage said tripping device to cause the same to operate the said clutch rotatably in the opposite direction and gearing for transmitting the rotations of said reversing clutch to the said counter.

5. In apparatus for integrating the value of a variable with respect to time, a counter for indicating the value of the variable being integrated, a timing gear, means for driving the same uniformly at a speed representative of time, a device for transmitting the rotations of the timing gear to the said counter to operate the latter alternately in an additive direction and in a subtractive direction, a tripping lever carried by and rotatable with said timing gear, a trip element fixedly mounted with relation to said tripping lever and adapted to be engaged by said lever to cause the said transmitting device to operate the counter in the additive direction, a movable trip element adapted to engage said tripping lever to cause said transmitting device to operate the counter in the subtractive direction and a gear connected to said movable trip element to operate the same to engage said tripping lever in timed relation proportional to the value of the variable being integrated.

6. In apparatus according to claim 5 in which the said two gears, the said transmitting device and the said tripping lever are mounted to rotate in operative relation about a common axis.

BERNARD E. SALTZMAN.
